UNITED STATES PATENT OFFICE.

JOHN H. HARDCASTLE, OF GOODLETTSVILLE, TENNESSEE.

CURRENT MOTOR.

Application filed January 25, 1927. Serial No. 163,459.

This invention relates to current motors. An important object of the invention is to produce a device of this character which may be very readily and cheaply manufactured and installed and which is of such structure that adjustments may be readily made to compensate for rise and fall of the stream in which it is disposed.

A further object of the invention is to provide a novel and improved bucket construction for use in connection with motors of this character.

A still further object of the invention is to provide a device for deflecting the heavy débris, so that the current motor may be located in the proper channel of the stream and heavy débris prevented from coming into contact with the buckets thereof or otherwise interfering with the operation.

These and other objects I attain by the construction shown in the accompanying drawings, wherein for the purpose of illustration is shown a preferred embodiment of my invention and wherein:

Figure 1 is a side elevation partially in section of a current motor constructed in accordance with my invention;

Figure 2 is a section on the line 2—2 of Figure 1;

Figure 3 is a front elevation of the deflector;

Figure 4 is an enlarged sectional view through one of the buckets.

Referring now more particularly to the drawings, the numerals 10, 11 and 12 indicate vertical standards embedded at their lower ends in the bottom of the stream aligning longitudinally of the current path. The upstream face of each support 10, 11 and 12 is provided with a vertically extending track 13 in which is slidably mounted a bearing 14 for a transversely extending shaft 15, the ends of which are provided with sprockets 16 well spaced from the side faces of the support. The bearings 14 are vertically adjustable by means of screws 17 rotatably connected with the bearings 14 at their lower ends and at the upper ends of the supports passing through fixed nuts 18. The upper ends of these screws will be provided with hand wheels 19 or any other suitable means for rotating the screws to provide proper adjustment of the bearings 14.

Each shaft 15 has secured thereto a gear 20 meshing with a gear 21 upon the lower end of a telescopic shaft, the sections of

which are indicated at 22 and 23. The section 22 or lower section is rotatably mounted in a vertically directed bearing 24 carried by the associated bearing 14, while the section 23 is rotatively mounted in a vertically directed bearing 25 fixed to the upper end of the associated support. From the upper ends of the sections 23, a drive may be taken off. In the present instance, I have shown the upper end of each shaft section 23 as equipped with a gear 26 meshing with a gear 27 upon a longitudinally extending shaft 28. This shaft may be equipped with pulleys 29 or any suitable drive take-off devices.

The sprockets, upon corresponding ends of the shafts 15, are connected by sprocket chains 30, each having secured thereto a series of longitudinally spaced bellows-like buckets, generally indicated at 31. These buckets, which are preferably of considerable length, each include a chain engaging wall formed in a plurality of sections, alternate sections being rigid, as indicated at 32, while the intervening sections are flexible, as indicated at 33. This provides a structure permitting the bucket wall to be made of a length greater than the length of the links 34 of the chain and at the same time permits ready passage of this wall about the curved paths formed by the passage of the chains over the endmost sprocket. The outer wall 35 of the bucket is rigid and is connected to the inner wall by a flexible bellows-like wall 36. With the chains moving in the direction of the arrows of Figure 1, the outer wall of each bucket, as the bucket passes over the right-hand sprocket, drops by gravity and is positioned to receive the force of the current. As the bucket passes over the left-hand sprocket, any water contained therein is discharged and the bucket collapses by gravity until it occupies the closed position illustrated.

It will be obvious that where a device of this character is made of any considerable length, there will be a tendency of the lower runs of the chains 30 to sag and leave the central sprocket. While this sagging will not interfere with operation, if it becomes excessive, it will have a tendency to cause undue strain and wear upon the parts. For this reason, I connect to the bearing 14 of the standard 11 a slide 37 having arms 38, the ends of which underlie the chains and are provided with supports 39 extending longitudinally of the chains. It will be ob-

vious that this slide being fixed to the bearing 14 will always have a fixed relation to the central sprocket and will provide a means for limiting the separation of the buckets from the central sprockets.

In order that heavy drift may be prevented from coming into contact with the mechanism, I secure to the bearing 14 associated with the standard 10 a rigid arm 40 projecting horizontally upstream from the standard and having rotatably mounted upon its upstream end a unit including a gear 41 and a plurality of radiating arms 42. This arm provides bearings 42^a for a shaft 43, the downstream end of which is provided with a gear 44 meshing with the associated gear 21 and the upstream end of which is provided with a gear 45 meshing with the gear 41. The outer end of the arm 40 has secured thereto the lower end of a brace 46, the upper rear end of which is in the form of a collar engaged with the screw 17 of the standard 10.

It will be obvious that during operation, the arms 42 will be slowly rotated and by their engagement against drift will deflect it to one side, so that it will not come into damaging contact with the mechanism.

Since the construction hereinbefore set forth is capable of a certain range of change and modification without materially departing from the spirit of the invention, I do not limit myself to such specific structure except as hereinafter claimed.

35 I claim:—

1. A current motor comprising a plurality of standards aligned longitudinally of the current, a horizontal bearing vertically adjustable upon each standard and directed transversely thereof, a shaft rotatably mounted in each bearing, sprockets carried by opposite ends of each shaft, chains engaging corresponding sprockets of said shafts, buckets carried by the chains, an arm extending forwardly from the support or standard arranged furthest upstream, a rotatable deflector carried by said arm and extending transversely of the current and a driving

connection between said deflector and one of said shafts.

2. A bucket for current motors comprising a pair of walls hingedly connected at one end and a flexible connection between said walls at the side edges thereof, one of said walls being rigid, the other of the walls being formed in alternate rigid and flexible sections.

3. A current motor comprising a plurality of standards aligned longitudinally of the current, a horizontal bearing vertically adjustable upon each standard and directed transversely thereof, a shaft rotatably mounted in each bearing, sprockets carried by opposite ends of each shaft, chains engaging corresponding sprockets of said shafts, buckets carried by the chains, a horizontal shaft extending longitudinally of the upper ends of the supports and a drive connecting each of the first named shafts with the last named shafts, each of said drives including telescopic shaft sections.

4. A current motor comprising a plurality of standards adapted to be aligned longitudinally of the current, a guide carried by the upstream face of each standard, a bearing slidable in the guide, a screw rotatably engaged at its lower end with the bearing, a fixed nut at the upper end of each standard through which the associated screw is directed, a transversely extending shaft carried by each bearing, sprockets carried by opposite ends of each shaft, chains carried by the sprockets, buckets carried by said chains, a horizontal shaft extending longitudinally of the upper ends of the standards and having a gear thereon for each standard, a gear secured to the shaft of each bearing and a vertically extending shaft carried by each standard including telescopic sections one having a gear meshing with the corresponding gear of the longitudinally extending shaft and the other meshing with the gear of the associated bearing.

In testimony whereof I hereunto affix my signature.

JOHN H. HARDCASTLE.
